UNITED STATES PATENT OFFICE.

HENRY BUHL WINTER, OF PUNXSUTAWNEY, PENNSYLVANIA.

WRENCH.

1,341,094.

Specification of Letters Patent.

Patented May 25, 1920.

Application filed September 11, 1918. Serial No. 253,534.

To all whom it may concern:

Be it known that I, HENRY B. WINTER, a citizen of the United States, and a resident of Punxsutawney, in the county of Jefferson and State of Pennsylvania, have invented certain new and useful Improvements in Wrenches, of which the following is a specification.

My invention is an improvement in wrenches, and has for its object to provide a wrench wherein a fixed jaw is provided with a movable jaw adjustable toward and from the fixed jaw with a coarse and a fine adjustment, the said adjustments being independent of each other.

In the drawings:

Figure 1 is a side view of the improved wrench, with parts broken away;

Fig. 2 is a partial longitudinal section, with the movable jaw in tilted position to release the coarse adjustment;

Fig. 3 is a section on the line 3—3 of Fig. 1, looking in the direction of the arrows adjacent to the line;

Fig. 4 is a top plan view of the fixed jaw and the adjacent portion of the shank.

In the embodiment of the invention shown in Figs. 1 to 3, the improved wrench comprises a shank 1 having at one end a fixed jaw 2 which may be integral therewith, and having at the other end a grip 3 which may be of wood or like material suitably connected to the shank.

The shank has a guide groove 4 on that face adjacent to the gripping portion of the jaw 2, the said groove extending from near the grip to near the fixed jaw, as shown in Figs. 2 and 4, and within this groove is arranged a rack bar 5, the said bar having two series of teeth 6 and 7, respectively. At the teeth 7 the bar is reduced as shown, so that the series of teeth 7 will lie closer to the shank than the series 6. The movable jaw 8 has a cuff or bearing 9 which fits loosely over the shank to permit the movable jaw to slide freely thereon. There is some play between the shank 1 at the end adjacent to the fixed jaw and the bearing 9, and a greater degree of play between the same and the other end of the bearing so that the movable jaw 8 may be tilted to a relatively large

extent with respect to the shank, as indicated in Fig. 2.

A plate spring 11 is secured to the bearing 10 in such position that it will bear against the shank between the bearings 9 and 10 and will normally act to hold the movable jaw 8 with the axes of its bearings 9 and 10 parallel with the axis of the shank 1, that is, in the position of Fig. 1.

A worm 12 is journaled on a ferrule 13 at the inner end of the grip 3, and this worm engages the series of teeth 7, to move the rack bar 5 toward the fixed jaw. A block 14 is connected to the movable jaw, being arranged within a recess at the end thereof remote from the fixed jaw, and this block carries a tooth 15 which is adapted to engage the teeth of the series 6, and it will be noted that these teeth incline toward the fixed jaw, while the teeth 15 incline in the opposite direction.

In use, in order to attain the coarse adjustment, the movable jaw is tilted in the manner shown in Fig. 2, to release the tooth 15 from the teeth 6, and the movable jaw is moved toward the fixed jaw to engage the object. When so engaged, the tooth 15 is permitted to engage the teeth 6, after which the fine adjustment may be attained by means of the worm 12.

In order to release the wrench from the object with which it is gripped, it may be necessary to utilize the fine adjustment, namely, the worm 12, at first. As soon as the movable jaw is loosened it is grasped and tilted, as shown in Fig. 2. Now the cam lever 16 will ride over the teeth 6 when the movable jaw is moved toward the grip. Due to the action of the cam lever, the possibility of accidental engagement of the teeth 6 and 15 in the opening movement of the movable jaw is greatly decreased, inasmuch as such engagement of the cam 16 and teeth 6 tends to keep the movable jaw in tilted position.

I claim:

A wrench comprising a shank having at one end a fixed jaw, a rack bar mounted to slide on the shank toward and from the fixed jaw, means for moving the rack bar in either direction, a movable jaw having a bearing engaging over the shank and the

rack bar and having a tooth for engaging the teeth of the rack bar and moved to release position by tilting the movable jaw, a spring for yieldingly holding the tooth in engagement with the teeth, a spring-pressed cam lever mounted in the movable jaw and movable into operative and inoper-

ative position by the movement of the movable jaw from and toward the fixed jaw, said cam lever when in operative position 10 adapted to contact with the teeth during the movement of the movable jaw away from the fixed jaw.

HENRY BUHL WINTER.
